FLUSH TYPE FLOWER VASE ASSEMBLY
Otto S. Gill, 18 Clark St., West Haven, Conn.
Filed Mar. 14, 1960, Ser. No. 14,923
1 Claim. (Cl. 47—41)

This invention relates generally to cemetery flower vases and specifically is an improvement to that type of vase used in cemeteries where it is desirable to not have projecting portions above ground level.

In many cemeteries, especially government and military cemeteries, there have been regulations set forth proscribing flower vases of the type which extend above ground level. These regulations were instituted to reduce increasingly high maintenance costs. The use of power mowers and other such equipment is greatly facilitated when there are no above ground projections.

The structure of the present invention is comprised generally of an outside aluminum casting adapted to be set in the ground, and a removable extruded aluminum insert which is adapted to fit within the casting.

One important objective of this invention is to provide a flower vase assembly of the type described, having means to prevent dirt in sufficient quantities from entering and caking between the flower holder insert and the casting which would result in hindering the removable feature of the insert. Because flush type flower holders are at ground level, the problem of dirt adhesion and caking presents a very serious difficulty. Flower vases of the type described herein are manufactured to last many tens of years, and must stay operable even though not used for many years at a time. If dirt caking begins and is allowed to age for long periods, it will destroy the usefulness of the springs and, in many instances, will prevent the inner vase from being removed without destroying the flower vase assembly. This invention advances means to lessen the amount of dirt entering the assembly, and provides an exhaust route for that which does enter.

Another important objective of this invention is to provide means whereby ground water which enters the assembly will readily drain therefrom.

A still further and important objective of this invention is to provide a unique leaf spring retaining type device to prevent the inner vase insert from floating in the event of rain or ground water. The springs are attached to the casting in a manner to reduce the chances of the springs becoming inoperative due to caking dirt.

A still further objective of this invention is to provide finger grips on the insert to cooperate with finger depressions on the casting so as to aid in the easy removal of the insert. The finger grips on the insert are in the forms of beads which have the further objective of giving additional strength to the insert. The bead acts also as a spacer between the flower stems and the upper vase opening.

Further objectives and advantages of this invention will be apparent from the following description and claim wherein the construction, arrangement and co-operation of the several parts of the invention are set forth.

In the drawings:

FIG. 1 is an elevational view with parts broken away;

FIG. 2 is a plane view thereof;

FIG. 3 is a sectional view along the line 3—3 of FIG. 1 with the insert removed; and

FIG. 4 is a sectional view along the line 4—4 of FIG. 2, showing the interior of the outside container and the interior vase in phantom.

Referring now to the drawings, where like elements indicate like parts, the numeral 10 indicates the flower

2

vase assembly of this invention. The assembly is comprised of two basic parts; an aluminum casting 12 and a metallic flower holder insert 14 which is closed at one end 16. Note in FIG. 1 that the insert is in its upside down or in a not-used position. When there are actually flowers in the vase, the closed end 16 would be at the bottom of the casting 12 as shown in phantom in FIG. 4. The safety and practical advantages of storing the inner vase in the upside-down position are evident. The assembly, in this position, presents a smooth surface to ground level, and will not hinder the use of power equipment. Additionally, the bottom of the inverted vase will act as a blocking member to dirt and water.

The insert 14 is made preferably of an extruded aluminum and has interiorly directed beads 18 and 20 near the closed and open ends thereof. The exterior annular grooves formed by beads 18 and 20 serve to provide a finger grip to remove the insert. The beads also act as reinforcing members for the extrusion. The beads further prevent flower stems from rubbing on the edge of the insert opening. The edges of extrusions of this type are oftentimes sufficiently sharp to cut flower stems inclined against them.

The casting or outer vase 12 is preferably of a one-piece aluminum construction and is formed of a cylindrical body section 24, inwardly facing bottom flange 26 and an outwardly extending upper flange 28. Conveniently arranged about the periphery of flange 28 is an extension 30 having a flagstaff receiving aperture 32 therein. Finger receiving depressions 31 and 33 are formed in the flange so that the insert may be gripped for removal. It should be noted that beads 18 and 20 are at a distance from the respective ends of the insert so that in both positions at least one of the beads is in communication with the finger depressions, 31 and 32.

Circumferentially spaced about the periphery of casting 12 are longitudinally shaped spring-receiving depressions 34 and 36. Leaf springs 40 and 42 are adapted to reside in these depressions and are fastened at their upper ends by rivets 44 and 46. The springs 40 and 42 are designed to partially extend within the interior of casting 12 to a point where they will firmly engage the side wall of insert 14. The springs provide positive frictional engagement with the insert so that the insert will not float out of the casting in the event of ground water conditions. The springs are fastened to the casting only at their upper ends, this permits any dirt which might get behind the springs to freely fall to the bottom of the container rather than adhering between the springs and the bottoms of the depressions. This is an important feature of the invention because dirt which adheres behind the springs and ultimately cakes, will render the springs inoperative.

The depressions 34 and 36 form protrusions along the exterior of the casting 12. At the lower ends of these protrusions are lug extensions 48 and 50. The lugs are integral with the casting and have their lower surfaces tapered as shown by the numerals 52 and 54. The upper surfaces 53 and 55 are substantially flat. The lower taper facilitates placing the casting within an earth bore having approximately the same circumference as the casting. The flat surface will resist any upward movement from the bore.

The upper opening 60 of the casting 12 is defined by an inwardly extending dirt resistant lip 62. The lip 62 extends a short distance above the annular flange 28 and acts as a blocking member to surface dirt which might wash into the casting 12. The interior surface of the casting 12 is tapered at 64 so that the inside diameter of lip 62 is only slightly larger than the diameter of insert 14. The small distance 66 between the lip 62 and the

insert 14 is reduced to a point where only small amounts of foreign materials may enter.

A liberal annular space 68 is defined between the casting and the insert. This reduces the chance of dirt caking between the two members. If some dirt does cake, surface water in most instances will wash same to the bottom and cause it to drain out. The recessed springs permit full movement of the insert within the casting so that any adhering dirt may mechanically be shaken loose if desired.

The insert 12 rests on interior bottom lugs 70 and 72 which are spaced about the flange 26. The raised position of the insert provides liberal drainage openings between the insert and the casting so that water or loose dirt which may reach annular space 68 may be readily exhausted through bottom openings 74.

In operation, a small earth bore having a diameter and length approximately the same as that of casting 12 is removed from the area of the grave to be served. The casting is forced into the bore to a point such that flange 28 is at ground level.

The insert 14 is placed in the casting in the flower-receiving position (FIG. 4). A flagstaff may be placed in aperture 32 and extended into the ground for further support if necessary. After the flowers have died or otherwise served their purpose, they may be removed and the insert changed to the FIG. 1 position until there is further use for it.

In a general manner, while I have, in the above description, disclosed what I deem to be practical and efficient embodiments of my invention, it should be well understood that I do not wish to be limited thereto, as there might be changes made in the arrangement, disposition and form of the parts without departing from the principle of the present invention as comprehended within the scope of the accompanying claim.

I claim:

A flower vase assembly of the type having all portions thereof substantially below ground level comprising in combination, a cylindrical outer vase having a body section, an upper end and a lower end, a first outwardly extending flange about said upper end, said outwardly extending flange having a plurality of finger depressions

along the upper surface thereof, a second inwardly extending flange defining an opening at said lower end, a plurality of bosses extending upwardly from said second flange, a cylindrical inner vase having an outer diameter substantially less than the inner diameter of said body section of said outer vase and supported on said bosses in spaced relationship to said lower flange, said body section having radially spaced recesses about the interior thereof, a leaf spring in each of said recesses each having their upper ends fixedly secured in said recesses and their lower ends extending into the interior of said outer vase and against said inner vase thereby spacing said inner vase from said outer vase, and said outer vase having an inwardly and upwardly directed annular taper at its upper end defining an opening only slightly larger than the circumference of said inner vase such that foreign matter will be impeded from entering the space between said inner and outer vases, said inner vase having an inward bead around said open top in communication with said finger depressions whereby the inner vase may be readily gripped for removal, and said inner vase having a second bead around the closed end thereof such that when said inner vase is inverted and said open end is resting on said bosses said second bead is in communication with said finger depressions, and said inner vase having a length such that when one end thereof is resting on said bosses, the other end thereof is substantially in the plane defined by the outermost surface of said annular taper.
